CLAIM

The ornamental design for a shoe sole as shown and described.

DESCRIPTION

FIG. 1 is a top, front and left perspective view of a shoe sole showing my new design;

FIG. 2 is a top plan view thereof;

FIG. 3 is a bottom plan view thereof;

FIG. 4 is a left elevational view thereof;

FIG. 5 is a right elevational view thereof;

FIG. 6 is a front elevational view thereof;

FIG. 7 is a rear elevational view thereof; and,

FIG. 8 is a bottom, rear and right perspective view thereof.

1 Claim, 8 Drawing Sheets(56)
